ASA B. SEGUR, OF OAK PARK, ILLINOIS, ASSIGNOR TO GENERAL CABLE CORPORATION,
OF NEW YORK, N. Y., A CORPORATION OF NEW JERSEY

COIL TERMINAL ATTACHING APPARATUS

Application filed February 24, 1930. Serial No. 430,861.

This invention relates to improvements in equipment for the attachment of terminal wires to the leads of electrical coils.

An object of the invention is to facilitate manual operations by which permanent connections are made between the respective leads of an electrical coil and the terminal wires therefor.

Other objects and advantages of the invention will appear hereinafter.

An illustrative embodiment of the invention is shown in the accompanying drawings, in which:—

Fig. 1 is a plan view showing an ensemble of parts belonging to the invention;

Fig. 2 is a side elevation projected from Fig. 1, partly in section;

Fig. 3 is a front elevation of the lead holder and severing device; and

Fig. 4 is a plan view of the lead holder and severing device.

Referring to Figs. 1 and 2 of the drawings, there is disclosed an assemblage of members consisting of a bench 1 having a forwardly extending shelf 2; a coil holder consisting of a cradle 3 supported upon a post 4 that surrounds the shelf; a pair of water pots 5 disposed one upon each side of the cradle, there being corresponding brackets 6 for the water pots, and a block 7 on the post from which the brackets extend; a lead holder 8 and lead severing device 9 disposed at the front end of the shelf 2; and a solder pot 10 located at a point between the coil holder and the lead severing device. Upon the bench, located beyond the cradle 3 conveniently are positioned a pair of partitioned pans 25 in each of which are separately held, a supply of flux 26 and glycerine 27, or similar materials.

The cradle 3 of the coil holder is preferably shaped so that when a coil 30 (Fig. 2) is placed therein, it will be held inert by its own weight, and the water pots 5 preferably are of such miniature proportions and are so disposed as not to obstruct movement of the hands of the artisan, but hold sufficient quantities of water as will suffice to chill many of the soldered joints of the leads and their terminal wires, which are immersed therein upon being formed.

The terminal holder 8 (Figs. 3 and 4) consists of a pair of spaced jaws 31 fixed upon a bracket 32, and a lever 33 supported by a bolt 34 that extends through said bracket, the lever having a tongue 35 that is projected between the jaws 31 when the lever is in normal position. A retracting spring 36 is secured at one end to a post 37 and at its opposite end to an arm 38 on the lever, whereby the lever normally is held with its tongue 35 between the jaws 31. The lever 33 has a handle 39 by which it may be manipulated to withdraw the tongue from the jaws and thus permit insertion of the leads 40, of the coil, between the tongue and jaws, which leads are anchored in the holder upon release of the handle.

The severing device 9 consists of a series of knife blades 41 secured to a bracket 42 having a slotted foot 43 that is adjustably positioned on the shelf 2, there being screws 44 to secure the foot in place. The blades 41 are disposed side by side, the cutting edge of one blade being convergent with respect to the cutting edge of the next blade adjacent thereto, which cutting edges meet, or slightly overlap, at points spaced from the tips of the blades. The positions of the blades are such that when the leads 40 are stretched out from the coil 30 in the cradle 3, and are anchored in the lead holder, they extend between the corresponding blades and lightly contact with the cutting edges thereof.

The solder pot 10 is mounted on the top of a vertically movable post 45 that extends loosely through the shelf 2, and conveniently is of the electrically heated type, conductors 46 being provided for supplying current from a suitable source of energy for heating the pot. The lower end of the post 45 is fixed on a block 47 that has a horizontally disposed pipe 48 attached thereto through which the conductors extend. The block 47 has pivotal connection with one end of a beam 49, the opposite end of the beam having sliding connection with a bracket 50 on the leg 51 of the bench. Another beam 52 has pivotal connection at one end with the bracket 50 at a point beneath the block 47, and has at its

other end pivotal connection with a slide 53 that is loosely mounted on the pipe 48.

An operating lever 54 is pivoted on the bracket 50 and is connected at one of its ends with said beams 49 and 52 at points thereon midway between their ends by means of a link 55, there being a spring 56 disposed in connection with the lever 54 tending to restrain its movement so that the solder pot is held normally in its lowermost position spaced suitably distant from the leads 40 to permit unobstructed movement of the fingers of the artisan in attaching the terminal wires to the leads.

15 When the lever 54 is tilted upon its fulcrum 57 in opposition to the restraint of the spring, the beams 49 and 52 are actuated through the medium of the link 55, and the solder pot is thereby elevated. Conveniently, a pedal 58 is attached to the lever 54 by means of a connecting rod 59, for actuating the lever.

In utilizing the assembly described, the leads 40 of a coil 30 are first drawn out and stripped of their covering of insulating material, after which the coil is laid in the cradle 3, and the cleaned leads are stretched forwardly between the blades 41 of the severing device 9 and anchored in the holder 8.

30 Flux 26 is applied to the wires by dipping their ends into the pans 25 in which the flux is contained. During this operation the artisan moistens his fingers and thumbs with the glycerine 27, or other suitable reagent, by which injurious effects of the flux upon the hands of the artisan are averted. The terminal wires are then applied to the leads 40 by the artisan, simultaneously, both hands being used, one in applying one of the wires to the one lead, and the other in applying the other wire to its lead, the operations consisting in bearing downwardly upon the leads so that they are severed by the blades 41 and their surplusage thus removed, and then entwining the leads about their respective terminal wires by rolling them between the thumbs and fingers. The ends of the terminal wires having the leads entwined thereon are immersed in the solder pot which is elevated by applying pressure to the pedal 58, and immediately thereafter the soldered joints are plunged into the corresponding water pots 5 and thereby chilled to cause the soldered connections to quickly set.

55 The coil 30 is then removed from the cradle and finished by applying tubes, stickers or pieces of tape and labels in such manner as may be required, the terminal wires being bound to the body of the coil by the tape and stickers so that the wires extend from such points on the coil as desired.

The equipment herein set forth affords facility for performing the series of operations resulting in the attachment of the terminal wires to the leads of the coils.

It will be understood that the invention may be variously modified and embodied within the scope of the claims.

I claim:

1. Means for facilitating manual operations for attaching terminal wires to the leads of coils, comprising, in combination, a coil holder; an anchor spaced from said holder for securing the lead of a coil positioned in said holder; and a severing means between the anchor and holder, having cutting edges near which said leads extend when anchored, whereby said leads are severed upon pressure being applied thereto against said edges. 70

2. An equipment for facilitating manual operations in making joints between the leads of coils and terminal wires therefor, comprising, in combination, a coil holder suitably supported, an anchor for the leads of the coil spaced from said holder, and a severing means between the anchor and holder, having cutting edges that extend in close proximity to said leads when anchored, whereby said leads are held in such positions as to permit the artisan to ambidextrously apply corresponding terminal wires thereto and remove the surplusage therefrom by applying twisting movement and pressure simultaneously to said leads and terminals. 80

3. In equipment for use in making electrical joints connecting leads of coils and terminal wires therefor, the combination of a suitably supported coil holder, an anchor for holding the leads of a coil, while in the holder, in extended positions, a severing means consisting of blades having convergent cutting edges disposed between the holder and anchor and between which blades the coil leads extend while anchored, and a pot containing melted solder movable into operative position between the holder and severing device, whereby ambidextrous manipulations of the artisan in connecting the leads with corresponding terminal wires, and in soldering said connections, are facilitated. 90

4. The combination with a coil holder, of an anchor spaced from the holder for securing the leads of a coil positioned in the holder in extended positions, and a severing device having stationary divergent blades disposed between the holder and the anchor and in proximity to the extending leads and being operable to cut said leads to predetermined lengths upon manipulation of the leads. 100

5. The combination with a holder for a coil, of lead severing means having stationary blades spaced from the holder, and means for holding the leads of a coil positioned in the holder, whereby said leads are sustained in positions to be cut to predetermined lengths by the severing means upon manipulation of the leads. 110

6. Equipment for facilitating manual operation in soldering terminal wires to the leads of coils including a stationary coil holder, a lead severing device, a lead anchor, said device and anchor being spaced from said holder in the order named, and a pot containing melted solder movably supported so as to be projected into the space between the coil support and said severing device whereby the connections manually made between said wires and leads may readily be immersed in said solder.

7. Equipment for facilitating manual operation for making electrical joints between the leads of coils and terminal wires therefor consisting of a group of appliances including a coil holder, an anchor spaced from said holder for securing the leads of a coil when positioned in said holder in most favorable positions for manual attachment of terminal wires thereto, and a severing means having cutting edges disposed respectively in close proximity to said leads when anchored whereby said leads are severed when manual pressure is applied thereto against said edges.

8. In equipment for use in making electrical joints connecting leads of coils and terminal wires therefor, the combination of a suitably supported coil holder, an anchor for holding the leads of a coil, while in the holder, in extended position, a severing means consisting of blades having convergent cutting edges disposed between the holder and anchor and between which blades the coil leads extend while anchored, and means for making a permanent union between a lead and terminal wire movable into operable position between the holder and severing device, whereby ambidextrous manipulations of the artisan in effecting permanent connections between the coil leads and corresponding terminal wires are facilitated.

In testimony whereof I affix my signature.
ASA B. SEGUR.
